UNITED STATES PATENT OFFICE.

JESSEE SCHAEFFER, OF ALLENTEWON, PENNSYLVANIA.

HEDGE-TRIMMER.

1,262,393.

Specification of Letters Patent.

Patented Apr. 9, 1918.

Application filed August 18, 1917. Serial No. 187,008.

To all whom it may concern:

Be it known that I, JESSEE SCHAEFFER, a citizen of the United States, residing at Allentown, in the county of Lehigh and 5 State of Pennsylvania, have invented a new and useful Hedge-Trimmer, of which the following is a specification.

This invention relates to a hedge trimmer, and has for its primary object to provide a 10 machine of this character, wherein the cutter can be readily and conveniently adjusted for the true cutting of the hedge, either at the top thereof or at its sides with despatch, the cutter being readily adjustable with accuracy so as to assure the trimming of the 15 hedge at any desirable height and for presenting different designs or configurations thereto.

Another object of the invention is the provision of a machine of this character wherein the same can be manually pushed along 20 the hedge, so that the latter can be properly trimmed in an even and uniform manner without excessive labor on the part of the 25 operator of the machine.

The invention, furthermore, has for an additional object to improve machines of the indicated character, in varying particulars, to the end that efficiency in operation may 30 be promoted, as well as simplicity in construction and convenience of adjustment and control.

The invention will be particularly explained in the specific description following:

Reference is to be had to the accompanying drawing forming part of this specification, in which similar characters of reference indicate corresponding parts in all views.

40 Figure 1 is a side elevation of a hedge trimming machine constructed in accordance with the invention, a portion of the wheel plate thereof being broken away.

Fig. 2 is a front elevation partly in vertical transverse section showing by full lines 45 a portion of the cutter in horizontal position, and by dotted lines in vertical position.

Fig. 3 is a fragmentary horizontal sectional view showing a portion of the cutter in top plan.

Fig. 4 is a fragmentary detail enlarged elevation of the adjustable mounting of the cutter.

Fig. 5 is a fragmentary vertical sectional elevation thereof.

Fig. 6 is a vertical transverse sectional view through the cutter.

Fig. 7 is a fragmentary vertical detail sectional view through the ratchet pinion.

Fig. 8 is a pictorial view showing a hedge of one design cut by the trimming machine.

Fig. 9 is a view similar to Fig. 8 showing another design of the hedge.

In constructing a practical embodiment 65 of the invention in accordance with the illustrated example, the traction wheel A is provided, preferably comprising a rim 10 and a solid disk-like web 11 which constitutes the body of said wheel, the rim 10 being 70 formed with an external roughened tread 12 to prevent the slipping of the wheel when traveling upon a foundation or the ground. The rim 10 is formed at its inner periphery with teeth 13 constituting an internal gear, 75 while the web 11 centrally thereof is formed with a hub 14 through which is passed the center stub axle 15 for the wheel A, the axle being also passed through the angular side members 16 of a combined handle bar and 80 trail frame B, the members being secured at their upper ends to a handle bar 17 which carries the cross handles 18 as usual, while the lower ends of the member 16 are suitably slotted to adjustably receive the stub axles 85 19 of trailing rollers 20 which are journaled upon said axles and project laterally from opposite sides of the frame rearwardly of the wheel A.

In the open side of the wheel A, or fitted 90 in the hollow portion thereof, is a circular or disk-like wheel plate or cheek 21 which is formed centrally thereof with a hub 22 to encircle the stub axle 15 and corresponds with the hub 14 of the wheel A, the wheel plate or cheek 21 being formed near its periphery with an arcuate shaped slot 23 in which is adjustably mounted a securing bolt 24 which is engaged and carried in one of the members 16 of the frame B, so that in 100 this manner said frame can be readily adjusted to vary the angular disposition of the handle bar 17, as will be clearly obvious.

Riveted, or otherwise fixed to the wheel plate or cheek 21 forwardly of the pivotal axis of the trail frame B, is a standard or upright 25 which is of the required length, and at its upper end is formed with an out-

turned ear 26 at right angles thereto forming a bearing for a driven shaft 27 which extends into and at its lower end is journaled interiorly of a gear casing 28, which is mounted upon the wheel plate or cheek 21 to inclose a pinion 29 loosely mounted upon the shaft 27 and meshing with a bevel gear 30 which is housed within said casing 28, and is fixed to a stub shaft 31 journaled 5 transversely in a stub bearing 32 formed on the inner face of the wheel plate or cheek 21. The stub shaft 31 is also fitted or formed with a cog gear 33 which meshes with the internal gear 13 on the traction 10 wheel A, so that on rotation of the latter, motion will be imparted to the shaft 27. The pinion 29 is fitted with a ratchet pin 34 which engages in a ratchet collar 35 pinned or otherwise secured to the shaft 27, so that 15 on the rotation of the pinion 29 in one direction, it will automatically lock with the collar 35 for the positive rotation of the shaft 27 from the traction wheel A, but on reverse rotation of the traction wheel A, the 20 shaft 27 will remain passive, the pinion 29, ratchet pin 34 and ratchet collar 35 being clearly shown in Fig. 7 of the drawing.

Slidably mounted upon the upright or standard 25 is an adjustable head comprising 25 side plates 36 which are bolted or otherwise secured together and have formed thereon guide cleats 37 which engage with the upright or standard 25, as clearly shown in Fig. 3 of the drawing, and mounted between these plates 36 are vertically spaced 30 cross straps or bearings 38 between which is located a spiral gear 39, the same being splined or keyed for longitudinal sliding movement on the shaft 27 which extends 35 through the bearings 38, so that said head is readily adjustable upon the upright or standard 25.

Meshing with the spiral gear 39 is a spiral threaded wheel 40 which is fixed to a stud 45 shaft 41 journaled in the plates 36 of the head transversely thereof. Swingly supported upon the stud shaft 41 of the wheel 40 is the adjustable cutter, which comprises a finger bar 42 and the sickle or cutter bar 50 43, which is suitably mounted for reciprocation upon the finger bar 42, and this cutter may be either straight or of arcuate formation for the cutting or trimming of the hedge into variable designs. The inner end 55 of the finger bar 42 is formed with a circular shaped hinge ear 44 which is rotatably supported on the stud shaft 41, and the periphery of this ear is formed at intervals with notches 45 for the engagement in any 60 one of the same of a hand-operated lock 46, so that the cutter can be secured in various angular positions, or perpendicular, or horizontal as occasion may require when cutting a hedge.

65 Secured to the stud shaft 41 at one side of

the spiral wheel 40 is an eccentric 47 embraced by the eccentric strap 48 formed with a pitman or throw-arm 49 which is pivotally connected at 50 to the sickle or cutter bar 43, so that on rotation of the eccentric 70 the cutter bar will be actuated for the reciprocation thereof upon the finger bar 42 for the cutting of a hedge, either at the sides thereof or at the top of the same. The cutter extends laterally from one side of the 75 upright or standard 25, the ear 44 being stamped or otherwise marked with suitable scale numerals 51 to enable the operator to determine with accuracy the adjustment of the cutter.

Carried by the head and mounted in the plates 36 thereof is a manually operable cam lock 52 which is thrown into and out of engagement with the upright or standard 25 for the locking or unlocking of the head 85 thereon, so that the cutter in this manner can be vertically adjusted to any desirable height.

Suitably connected to the head at one of the plates thereof is a raising and lowering 90 cable 53 which is adapted to be secured to and wound on and from one of the handles 18 which constitutes a windlass therefor, so that the cutter and its head can be conveniently vertically adjusted or raised and lowered at the option of the operator of the machine, it being understood, of course, that the handles 18 are rotatably supported upon the handle bar 17 in the usual well known manner.

The cable 53 is trained through a guide device 54 on the ear 26 of the standard 25 so that on the winding of the cable upon the handle 18 by rotating the latter, the head will be raised on the said standard and upon 105 the unwinding of the cable from said handle in the same manner, the head will be lowered upon the standard, thereby adjusting the height of the cutter to meet the demand in properly cutting the hedge.

Thus, it will be observed that the cutter may be readily adjusted and controlled to cut either one side of a hedge, from top to bottom, or cut quite across the top of the hedge from side to side thereof, and the adjustment of the cutter is under the complete control of the operator of the machine, and, furthermore, the hedge can be trimmed to present various designs or contour thereto when the machine is active.

From the foregoing it is thought that the construction and the manner of the operation of the machine will be clearly understood, and, therefore, more extended explanation will be omitted.

The construction shown herein is the preferred embodiment of the invention, but I do not wish to be limited to the form, size, proportion and minor details of construction as such changes may be made in the in- 125 130

vention, in the particulars mentioned, without departing from the spirit or scope of the invention as defined in the appended claims.

What is claimed is:

- 5 1. A hedge trimming machine comprising a single traction wheel, a trailer frame adjustably supported upon said wheel, and having trailing rollers at opposite sides of the frame, a handle bar on said frame for 10 manually propelling the machine, a standard supported vertically forwardly of the frame at one side of the wheel, a head adjustable on the standard, a cutter adjustably connected to the head, and connections between the traction wheel and the cutter for 15 operating the latter and driven by the wheel exteriorly thereof.

2. A hedge trimming machine comprising a traction wheel, a trailer frame adjustably supported upon said wheel, and having trailing rollers, a handle bar on said frame for manually propelling the machine, a standard supported forwardly of the frame, a head adjustable on the standard, a cutter 25 adjustably connected to the head, connections between the traction wheel and the cutter for operating the latter, and means extending from the head to the handle bar for raising and lowering the head.

- 30 3. A hedge trimming machine comprising a single traction wheel, a frame on which said wheel is journaled, trailing means, a handle bar on said frame for manually propelling the machine, a vertical standard, a head vertically adjustable on the standard, a cutter connected to the head, and driving 35 connections between the traction wheel and the cutter for operating the latter.

4. A hedge trimming machine comprising 40 a single traction wheel, a frame on which said wheel is journaled, trailing rollers mounted on opposite sides of the vertical plane of the said wheel, a handle bar on said frame for manually propelling the machine, a vertical standard, a head vertically adjustable on the standard, a cutter carried by said head, a vertical shaft arranged alongside said standard, and driving gear connections between the traction 45 wheel, the shaft and said cutter.

5. In a hedge trimming machine, a traction wheel, a trailing frame having the traction wheel journaled therein, a wheel plate supported upon the journal of the traction wheel, and fitted within the latter, a vertical standard fixed to the wheel plate, a gear casing carried by the plate, a vertical shaft journaled on the standard and said gear casing, gear connections between the 55 shaft and said traction wheel, a head 60 slideable on the standard, a spiral gear supported in the head and slidably keyed to the shaft, a spiral wheel journaled in the head and meshing with the spiral gear, a cutter swingingly supported on the head, and ec-

centrically operated connections between the spiral wheel and the cutter for actuating the latter.

6. In a hedge trimming machine, a traction wheel, a trailing frame having the traction wheel journaled therein, a wheel plate supported upon the journal of the traction wheel, and fitted within the latter, a standard fixed to the wheel plate, a gear casing carried by the plate, a vertical shaft 70 journaled on the standard and said gear casing, gear connections between the shaft and the traction wheel, a head slideable on the standard, a spiral gear supported in the head and slidably keyed to the shaft, a spiral wheel journaled in the head and meshing with the spiral gear, a cutter swingingly supported on the head, eccentrically operated connections between the spiral wheel and the cutter for actuating the latter, a handle bar on the trailing frame, and raising and lowering means extending from the handle bar and connected with the head. 80

7. A hedge trimming machine comprising a single traction wheel, a frame provided with trailing rollers and having the traction wheel journaled therein, a wheel plate for the traction wheel, a vertical standard fixed to the wheel plate, a cutter mounted on the standard, a vertical shaft arranged alongside the standard and driving gear connections between the traction wheel, the shaft and the cutter. 90

8. In a hedge trimming machine, the combination with the traction wheel, a frame 100 having the traction wheel journaled therein, a fixed vertically disposed standard, a vertical shaft journaled on the standard and arranged alongside the same, gear connections between the shaft and the traction 105 wheel, a head slideable on the standard, a spiral gear supported in the head and slidably keyed to the shaft, a spiral wheel journaled in the head and meshing with the spiral gear, a cutter swingingly supported 110 on the head, and eccentrically operated connections between the spiral wheel and the cutter for actuating the latter.

9. A hedge trimming machine comprising an internally toothed traction wheel, a frame 115 having the wheel journaled therein, a ground roller carried by said frame, a plate for the wheel, a standard fixed to the plate, a head adjustable on the standard, a cutter carried by said head, a driving shaft supported 120 alongside the standard, gear connections between the shaft and the internal teeth of said wheel, and other gear connections between the driving shaft and the cutter.

10. In a hedge trimming machine, a traction wheel, a trailing frame having the traction wheel journaled therein, a wheel plate supported upon the journal of the traction wheel and fitted within the latter, a standard fixed to the wheel plate, a gear casing 125

carried by the plate, a vertical shaft journaled on the standard and said gear casing, gear connections between the shaft and the traction wheel, a head slideable on the standard, a spiral gear supported in the head and slidably keyed to the shaft, a spiral wheel journaled in the head and meshing with the spiral gear, a cutter swingingly supported on the head, eccentrically operated connections between the spiral wheel and the cutter for actuating the latter, a handle bar on the trailing frame, raising and lowering means extending from the handle bar and connected with the head, trailing rollers journaled on said frame, means for locking the head in adjusted position on the standard, and means adjustably securing the trailing frame upon the gear plate.

11. In a hedge trimming machine, a traction wheel, a trailing frame having the traction wheel journaled therein, a wheel plate supported upon the journal of the traction wheel, a vertical standard fixed to the wheel plate, a vertical shaft journaled on the standard, gear connections between the shaft and the traction wheel, a head slideable on the standard, a spiral gear supported in the head and slidably keyed to the shaft, a spiral wheel journaled in the head and meshing with the spiral gear, a cutter swingingly supported on the head, eccentrically operated connections between the spiral wheel and the cutter for actuating the latter, a handle bar on the trailing frame, raising and lowering means extending from the handle bar and connected with the head, trailing rollers journaled on said frame, means for securing the cutter in adjusted position on the head, means for locking the head in adjusted position on the standard, and a one-way ratchet connection between the gearing and said shaft.

12. A hedge trimmer having a single traction wheel, a plate fixed in the wheel, a standard on the plate, a cutter having vertically sliding and swinging connection with the standard, and means for operating the cutter and driven interiorly of said wheel.

13. A hedge trimming machine comprising a single traction wheel, a frame provided with trailing rollers and having the traction wheel journaled therein, a wheel plate for the traction wheel, a vertical standard fixed to the wheel plate, a head slideable on the standard, a cutter connected to the head, and driving connections between the traction wheel and the cutter for operating the latter.

14. In a hedge trimming machine, a trac-

tion wheel, a trailing frame having the traction wheel journaled therein, a wheel plate supported upon the journal of the traction wheel, a vertical standard fixed to the wheel plate, a gear casing carried by the plate, a vertical shaft journaled on the standard and said gear casing, gear connections between the shaft and the traction wheel, a head slideable on the standard, a spiral gear supported in the head and slidably keyed to the shaft, a spiral wheel journaled in the head and meshing with the spiral gear, a cutter swingingly supported on the head, and eccentrically operated connections between the spiral wheel and the cutter for actuating the latter.

15. In a hedge trimming machine, a traction wheel, a trailing frame having the traction wheel journaled therein, a wheel plate supported upon the journal of the traction wheel, a vertical standard fixed to the wheel plate, a vertical shaft journaled on the standard, gear connections between the shaft and the traction wheel, a head slideable on the standard, a cutter swingingly supported on the head, and a hand operated lock for securing the cutter for various positions.

16. A hedge trimming machine embodying a single traction wheel having an internal gear with trailing rollers constituting the sole support for the machine and manually movable, the combination therewith of means for supporting a cutting mechanism at one side of the plane of said wheel in offset relation, and movable therewith and sufficiently high to cut a hedge, and means for driving said cutting mechanism directly from the internal gear of said traction wheel.

17. In a manually-propelled hedge trimming machine embodying a single traction wheel with trailing means disposed on opposite sides of the vertical plane of said wheel, and constituting the sole support for the machine, and a handle bar connected to the wheel for manually moving the machine, the combination therewith, of means for mounting a cutting mechanism at one side of the plane of said wheel in offset relation and movable therewith, and means for driving said cutting mechanism directly from the said traction wheel.

In testimony, that I claim the foregoing as my own, I have hereto affixed my signature in the presence of two witnesses.

JESSEE SCHAEFFER.
